UNITED STATES PATENT OFFICE

CHARLES M. COLVIN, OF WILMETTE, ILLINOIS

OIL-BURNING APPARATUS

Application filed December 18, 1925. Serial No. 76,308.

My invention relates to oil burning apparatus and has among its other objects the production of apparatus of the kind described which is compact, convenient, durable, 5 efficient and satisfactory for use wherever found applicable.

A particular object of the invention is to provide improved apparatus for continuously mixing liquid fuel and air in definite proportions.

Another particular object of the invention is to provide oil burning apparatus having improved construction for insuring a sufficient supply of oxygen for the flame.

One form of the invention is embodied in 15 a heating unit comprising a hot air furnace, a tank for holding liquid fuel, motor driven oil and air pumps, and a float chamber, which, with the exception of an oil inlet, an air inlet, 20 and an outlet for mixing oil and air is substantially air tight, the outlet being connected to a nozzle which projects into the fire pot of the furnace in such manner that flame issuing from its flame orifice passes the 25 posterior ends of passages provided in the fire pot and causes air to be drawn through them from the space beneath the fire pot.

Many other objects and advantages of the construction herein shown and described will 30 be obvious to those skilled in the art from the disclosure herein given.

To this end my invention consists in the construction, arrangement and combination of parts herein shown and described, and 35 more particularly pointed out in the claims.

In the drawings, wherein like reference characters indicate like or corresponding parts:

Fig. 1 is an elevation of oil burning apparatus embodying the invention;

Fig. 2 is a section taken on line 2—2 of Fig. 1;

Fig. 3 is an enlarged section taken through a float chamber forming part of the apparatus shown in Fig. 1; and

Fig. 4 is a section taken on line 4—4 of Fig. 1.

In the drawings I have shown a preferred form of the invention embodied in apparatus 50 which comprises a furnace 10 of the hot air

type, but it is to be understood that the invention is not limited to furnaces of this type, nor to furnaces in general, as it may be embodied in boilers and other heating devices. In this embodiment of the invention, the furnace 10 comprises a fire pot 11 around which 55 a substantially annular chamber 12 is provided wherein air may be heated by bringing it in contact with a substantially cylindrical wall 13 forming part of the fire pot. The fire pot is preferably provided with a door 15 through which a nozzle 16 projects in such manner that flame issuing from its flame orifice will follow the inner surface of the cylindrical wall 13, the construction being 60 such that in practice the tip of the flame generally returns and passes the flame orifice. The purpose of this construction will presently appear.

The nozzle 16 is preferably supplied with 70 fuel under pressure by a conduit 17 or the equivalent, the conduit 17 being preferably formed from relatively flexible or seamless drawn metallic tubing. The conduit 17 is connected by a union 19 to an elbow 20 screw-threaded into a housing 21 mounted upon a base 22 or the equivalent. A pipe fitting 23 is connected by a pipe nipple 24 to the interior of the housing 21 and by a pipe 25 to the outlet of an air pump 26, a gauge 27 75 mounted upon the pipe fitting 23 being adapted to indicate the pressure obtaining within the housing 21. Disposed adjacent the air pump 26 is an oil pump 29 having an inlet port 30 connected by a pipe 32 to a tank 33 80 adapted to hold a supply of liquid fuel, such as crude oil. The oil pump 29 has a discharge port 35 which is connected by a pipe 36 and a by-pass pipe 38 with the tank 33. Obviously, there will be a continuous flow of 85 oil through the pipes 32 and 36 and 38 when the pump 29 is in operation. The pipe 36 communicates with the interior of the housing 21 through a by-pass pipe 38 and a tubular member 39 which is screw-threaded 90 into the housing.

Any suitable means may be provided for driving the pumps 26 and 29. Thus, I have shown an electric motor 40 directly coupled to the pumps, the motor 40 being mounted 95

upon the base 22 which also supports the pumps.

Referring now to Fig. 3, it will be noted that the housing 21 is substantially air-tight with the exception of the openings provided in it for the elbow 20, the pipe nipple 24 and the tubular member 39. The housing forms a chamber 42 which may be regarded as a float chamber and a mixing chamber, a float 44 disposed within the chamber being adapted to cooperate with other mechanism to maintain the fuel at a substantially constant level within the chamber so that air entering it by way of the pipe 25, the pipe fitting 23 and the nipple 24 may vaporize a definite quantity of oil and deliver it to the nozzle 16. The mechanism cooperating with the float 44 preferably comprises a lever 45 pivoted intermediate its ends and having one end adapted to engage the float, the other end of the lever being engageable by a valve stem 46 having a needle valve 47 formed at its lower end. The needle valve 47 is adapted to engage a valve seat 48 formed at the upper end of the tubular member 39 and thus controls the flow of oil into the chamber 42. The construction is such that the oil is normally maintained at a level indicated by the dotted line 50.

As shown, the elbow 20 is preferably provided with an extension 52 which projects into the chamber 42. Screw-threaded into the extension 52 is a tube 54 which in this embodiment of the invention projects beneath the oil level 50. The upper end of the tube 54 is aligned with a hole 55 extending transversely through the extension 52. It is readily understood that when the pump 26 forces air into the chamber 42 through the nipple 24, the air passes to the nozzle 16 by way of the hole 55, the elbow 20 and the conduit 17. It is also readily understood that the tube 54 will then function as a jet and a definite quantity of oil will be forced into the elbow 20 with the air entering through hole 55 into the elbow, the oil being vaporized or finely atomized when it mixes with the air.

As mentioned above, the flame which issues from the nozzle 16 when the apparatus is in operation follows the inner surface of the cylindrical wall 13. I preferably provide fire-brick 58 or the equivalent at that point where the flame tends to impinge upon the cylindrical wall 13 so as to prevent that portion of the wall from being burned out. A bottom wall 59 provided in the fire pot 11 is preferably provided with a central aperture 60 through which the fire pot communicates with the lower portion of the furnace so that air may be drawn therefrom to supply oxygen to the flame. To increase the flow of air through the aperture 60, I prefer to form a plurality of passages 62 in the fire pot, the inner ends of the passages 62 opening directly into the aperture. The passages 62 may be

formed by placing bricks 64, or the equivalents for the purpose, upon the bottom wall 59 of the fire pot. The arrangement is such that the draft caused by the flame as it passes the outer ends of the passages 62 will cause air to be drawn from the lower portion of the furnace through the aperture 60 and the passages. The nozzle 16 is preferably adjustably mounted so that the path of the flame can be controlled to some extent. Thus, the door 15 is preferably apertured as at 67 to rotatably journal a pair of blocks 68 and 69 which are secured to each other by screws 70 or the equivalent. The nozzle 16 projects through aligned holes 71 formed in the blocks 68 and 69, the construction being such that the blocks may be revolved to raise or depress the nozzle.

As best shown in Figs. 1 and 4, I preferably provide an aperture 73 in the door 15 beneath the nozzle 16. Mounted on the outer side of the door and aligned with the aperture 73 is a pilot light 76 which is connected by a pipe 77 to any suitable supply of fuel, means being provided intermediate the pilot light and the pipe 77 to control the flow of fuel to the pilot light. This means may comprise a diaphragm (not shown) and a valve (not shown) mounted within a casing 79 which is connected by a pipe 81 to the aforementioned pipe fitting 23 so that compressed air may flow from the pipe 25 through the fitting 23 and the pipe 81 to the casing 79. The diaphragm (not shown) and the valve (not shown) are so constructed that when a predetermined pressure obtains within the pipe 81 fuel may flow from the pipe 77 to the pilot light 76, the valve (not shown) being adapted to cut off the supply of fuel when the pressure within the pipe 81 falls below the predetermined value. Aligned with the pilot light 76 is a pilot light 83, which preferably remains normally lighted, the pilot light 83 communicating with the pipe 77 through a by-pass pipe 84. In the event that the pilot light 83 is accidentally extinguished, a thermostat 86 functions to open an electrical circuit (not shown) including the motor 40 so that the apparatus will cease to supply vaporized fuel to the nozzle 16.

The operation of the above described apparatus is substantially as follows: The pilot light 83 normally remains lighted. The apparatus may be set in operation by closing the circuit (not shown) which includes the motor 40 and is adapted to connect it to any suitable source of electrical energy. The motor 40 then drives the pumps 26 and 29 so that the mixing chamber 42 will be continuously supplied with fuel and air, it being obvious that the float 44 will function to keep the oil at a constant level in the mixing chamber. The compressed air entering the mixing chamber does not vaporize any appreciable amount of oil until it passes

through the hole 55 in the elbow 20 and a jet of fuel is forced to flow from the tube 54. The compressed air vaporizes or finely atomizes this jet of fuel and delivers it to the nozzle 16 where it is ignited by the pilot light 76, the pilot light 76 being lighted by the pilot light 83 the moment the pressure within the pipe 81 rises to a predetermined value.

In practice, I preferably have the fuel enter 10 the chamber 42 under a pressure which exceeds the pressure under which the air enters the chamber. I have found that by feeding the fuel into the chamber at thirty-five pounds pressure and by feeding the air into the chamber 15 at five pounds pressure, I can obtain efficient operation of the apparatus but I do not limit myself to these pressures. The proportions of the mixture supplied to the nozzle may be varied to suit any conditions or to 20 suit the desires of the user as the tube 54 may be adjusted in the extension 52 of the elbow 20 to vary the amount of fuel which the air will force into the elbow. I find that after the apparatus has been adjusted to deliver 25 a mixture of certain proportions of fuel and air to the nozzle, these proportions will remain constant even though the pressure at which the air is supplied to the chamber 42 varies. Thus, if the pressure under which 30 the air is supplied falls, the air will force a proportionately smaller amount of fuel from the tube 52, and if the pressure rises, the air will force a proportionately larger amount of fuel from the tube.

Having thus described my invention, it is 35 obvious that various immaterial modifications may be made in the same without departing from the spirit of my invention; hence I do not wish to be understood as limiting myself to the exact form, construction, 40 arrangement and combination of parts herein shown and described or uses mentioned.

What I claim as new and desire to secure by Letters Patent is:

1. In apparatus of the kind described and in combination, a burner, a chamber, a tubular fitting projecting into said chamber from the top thereof and having an opening in its side wall communicating with the interior of the chamber, means connecting said fitting with said burner, a tube disposed within the chamber and adjustably carried by the fitting, the upper end of said tube being aligned with said opening in said tubular fitting, 50 means for supplying liquid fuel under pressure to the chamber, and means for supplying air under pressure to the chamber.

2. In apparatus of the kind described and in combination, a burner, an air-tight chamber, a tubular fitting projecting into the chamber from the top thereof and having an opening in its side wall communicating with the interior of the chamber, means connecting said fitting with said burner, a tube 60 depending from said fitting and adjustably

secured thereto, the upper end of said tube being aligned with said opening in said fitting, means for supplying liquid fuel under pressure to the chamber, and means for supplying air under pressure to the chamber. 70

3. In apparatus of the kind described and in combination, a burner, an air-tight chamber, a tubular fitting projecting into the chamber from the top thereof and having an opening in its side wall communicating with the interior of the chamber, means connecting said fitting with said burner, a tube depending from said fitting and adjustably secured thereto, the upper end of said tube being aligned with said opening in said fitting, 75 means for supplying liquid fuel under pressure to the chamber, means for supplying air under pressure to the chamber, and means for maintaining the liquid fuel at a constant level in the chamber, said level being below 80 said opening in said fitting.

4. In an apparatus for burning liquid fuel, a chamber, means for supplying liquid fuel to the chamber, means for maintaining the liquid fuel at a constant level in the chamber, 90 means for supplying air under pressure to the chamber, a tube disposed in said chamber and projecting into said liquid fuel in said chamber, and a tubular member into which said tube projects, said tubular member formed with an opening through its wall above said level and forming an outlet for the chamber through which the air passes, said fuel being atomized as it passes said opening. 95

5. In an apparatus of the kind described, a chamber, a tubular fitting projecting into said chamber and having an opening in the side wall thereof, a tube threadedly engaging said tubular fitting and having an end portion for controlling the size of said opening, 100 means for supplying liquid fuel under pressure to said chamber and maintaining same at a constant level below said opening and above the end of said tube, and means for supplying air under pressure to said chamber. 105

In testimony whereof, I have hereunto signed my name.

CHARLES M. COLVIN.
